LIGHTER CONSTRUCTION

Alexander Harris, East Orange, N. J., assignor to
 Art Metal Works, Inc., a corporation of New
 Jersey

Application September 11, 1940, Serial No. 356,282

2 Claims. (Cl. 67—4.1)

This invention relates to pyrophoric lighters such as adapted for lighting cigarettes, cigars or pipes.

In its preferred form the invention provides a simple, inexpensive, durable and safe form of lighter which is particularly adapted for use over long periods of time, for example many months, without refilling the lighter with fuel and without requiring replacement of the pyrophoric sparking metal or any other special attention to the mechanism or its parts by the user.

In carrying out the invention, a suitable decorative form of container may be provided, the lower portion of which may contain a compartment filled with fuel absorbent material such as cotton. The top wall of this compartment may be suitably apertured to removably receive the outlet spout of a removable and replaceable fuel can located in inverted position within the upper portion of the container. The outlet opening of the fuel can may be filled with a length of wicking or the like material protruding downwardly somewhat from the can outlet to thereby contact with the fuel absorbent material in the compartment, thus keeping the latter material constantly saturated with fuel but without permitting the free running of the fuel out of the inverted fuel can. Suitable forms of lighting mechanism may be mounted upon or in association with the container such for example as a so-called striker type of pyrophoric lighter, or lighter mechanisms such as shown in the patents to Aronson Nos. 1,986,754 and 2,002,845.

By utilizing the arrangement above briefly outlined, fuel for the lighters may be marketed in cans of suitable size and having outlet openings or necks already filled with a suitable wicking member and so shaped as to be immediately insertable in the lighter ready for use upon removing a screw cap or seal for the can. The lighter thus being adapted to receive a full can of the fuel, it will be unnecessary for the user to refill the lighter for a long period and when refueling is necessary, it may be very quickly accomplished by merely removing the old empty fuel can from the assembly, whereupon a new fuel can may be at once inserted as a unitary assembly without the danger and inconvenience of pouring the fuel from one receptacle to another and with assurance that none of the fuel will be spilled or lost by evaporation either during the refilling operation or later.

Various further and more specific objects, 55

features and advantages of the invention will appear from the detailed description given below, taken in connection with the accompanying drawing forming a part of this specification and illustrating merely by way of example certain embodiments of the invention. The invention consists in such novel features, arrangements and combinations of parts as are shown and described herein.

10 In the drawing,

Fig. 1 is a perspective view of one of the preferred and simple forms of the invention;

Fig. 2 is a vertical sectional view of the device of Fig. 1;

15 Fig. 3 is an elevational view partly in section, showing the outlet portion of one of the fuel cans adapted for use according to the invention;

Fig. 4 is a plan view partly broken away showing the outlet portion of one of the fuel cans after removal of the sealing cap;

Figs. 5 and 6 are top and vertical sectional views respectively of an alternative embodiment of the invention; and

25 Figs. 7 and 8 illustrate certain details of alternative forms of the invention.

In the particular form shown in Figs. 1 to 4 of the drawing, the device of the invention may include a suitable container 10, which may be decorated in any desired manner and having at its lower portion a compartment as at 11 filled with fuel absorbent material such as cotton for example. The upper portion of the container may be formed with a slidably removable and preferably firmly fitting cover portion as at 12, permitting replacement of fuel cans as at 13 which are positioned in the hollow upper portion of the container 10. The compartment for the fuel absorbent material may 30 be separated as by a horizontally extending wall or partition 14, from the receptacle cavity for receiving the fuel can. This wall 14 may be formed with a central aperture preferably surrounded by a downwardly projecting flange as 35 at 15. Such aperture is adapted to closely receive and embrace the outlet portion or neck 16 of the removable fuel can.

As shown in Fig. 3, the fuel cans 13 are preferably provided as an assembled unit ready for 40 use including a length of wicking or the like as at 17, extending down into the fuel in the can for example one inch or more, and also extending slightly out beyond the edges of the neck portion 16. This wick member if desired 45 may be permanently secured in its proper posi-

tion for use, against tampering and the possibility of spilling fuel, as by indentations or portions as at 18 struck inwardly from the walls of the neck portion 16 into engagement with the wicking material. The neck portion 16 may have a suitably threaded area as at 19 for receiving a sealing cap as at 20, the lower flanged or beaded edges 21 of which may engage a sealing gasket as at 22. It will be noted that the upper portion of the cap 20 is so shaped as to be adapted to receive the protruding portion of the wicking 17. Thus fuel "refills" suitable for convenient retail sale are provided in a form ready to be immediately inserted into the lighter upon removal of the sealing cap 20.

To insert such fuel "refills," it is merely necessary to remove the container cover 12 and to remove the older empty fuel tank 13, whereupon the "refill" with its cap removed, may be at once inserted in place of the used fuel can and the protruding wicking 17 will, because of its contact with the fuel absorbent material in the compartment 11, quickly cause the fuel absorbent material to become saturated so that the lighter will be immediately ready for further use. And all this may be accomplished without pouring or exposing any free fuel and thus fire hazards, inconvenience and spilling are avoided, while still making available in the lighter a reservoir of fuel large enough to serve the lighter for a long period of time. It will be further noted that even if the lighter should be tipped over or accidentally dropped, there will be no opportunity for this large amount of fuel to be spilled and the fuel is in effect protected in a double walled container while in the lighter, eliminating any likelihood of accidental damage such as would permit the fuel to leak out or be spilled.

The action of the wicking 17 in contact with the fuel absorbent material in the compartment 11 is such that while the absorbent material almost immediately becomes saturated upon insertion of a fuel container, yet once this material is saturated there is no further escape of fuel from the container except as required to gradually replace the fuel used for lighting purposes. That is, the arrangement is such that no free liquid accumulates within the compartment 11. Yet even if the wicking 17 should not properly contact with the fuel absorbent material because of tampering or otherwise, still no excessive amount of the fuel can escape from the can since any free body of fuel in the compartment 11 would soon rise to a level enveloping the wicking 17 as surrounded by the flange 15 and thus stop any further escape of fuel from the can by reason of the difference in atmospheric pressure inside and outside the can. The flow of fuel from the can is thus very accurately regulated in accordance with the needs of the lighter without danger that the fuel will run out on to and around the lighter mechanism and make possible a flame of dangerous size.

The particular form of pyrophoric lighting mechanism as shown in Figs. 1 and 2 is of the so-called striker type, including a torch member 23 adapted to normally rest in a receptacle or well portion 24 extending at a convenient angle upwardly and outwardly from the base of the lighter container. The torch assembly 23 may include a tapered neck portion 25, machined or ground to accurately fit in sealing relationship with a correspondingly tapered opening as at 26 in a member 27. The member 27 may be fixed in position as by threaded engagement at 28 with a

tubular portion 29, the lower edges of which may be welded or soldered in place as shown approximately at the juncture of the lower portion of the container 10 and its base portion or the compartment 11.

The torch assembly may also include a rod 30 of suitable length extending down through a central aperture in the member 27. This rod may be adapted to receive a tubular wick member 31 surrounding a suitable steel striker rod as at 32 protruding as shown from the end of the wick 31.

The torch assembly 23 will normally rest in the well portion or assembly as shown with its wick 31 contacting with the fuel absorbent in the compartment 11. Thus the wick 31 will be kept moistened with the fuel. In using the device the torch assembly may be slidably removed whereupon the striker portion 32 may be quickly drawn along a suitable bar of pyrophoric sparking metal as at 33 mounted upon the base of the device as shown. This will result in igniting the fuel on the wick 31 whereupon the torch is ready to be used for lighting cigarettes or pipes, etc. After use, the flame on the torch may either be blown out, or extinguished by reinsertion of the torch into the well assembly 24.

It will be understood that the pyrophoric elements may be associated with the assembly by mounting such elements at various other convenient locations on the compartment or can container, as may be desired, depending on the character of the decorations on the device or other factors.

Various modifications of torch assemblies and associated parts particularly adaptable for use with this invention are disclosed in the patents to Aronson Nos. 1,986,754, 2,104,964, 2,104,965, 2,120,226, 2,134,497 and 2,140,277.

If desired, two strips or bars of the pyrophoric sparking metal as shown at 33 and 33' may be mounted, one at either side of the base of the lighter. These strips are preferably embraced in protective casings of thin sheet metal as at 34 adapted to slidably and removably engage correspondingly slotted portions on the base of the lighter with a firm fit. The inner ends of the casing 34 may be provided with small extensions or lip portions as at 35 for facilitating removal of the sparking metal assemblies which may be sold at retail as assembled units for replacement purposes. However, the use of the two relatively long bars of the pyrophoric material will provide sufficient sparking metal so that ordinarily the same will not be so worn out as to need replacement except after, for example, several years' use. As shown, the areas upon which the bars of pyrophoric material are mounted may be preferably inclined somewhat with a gradual slope toward the user of the lighter to permit convenient striking action with the torch assembly.

While the arrangement shown in Figs. 1 and 2 will ordinarily effectively seal the fuel container against any measurable loss of fuel by evaporation, under some circumstances it may be desired to further insure against evaporation and escape of fuel. To further insure sealing of the receptacle 11 against evaporation around the torch receiving well, the base of the handle of the torch as shown in Figs. 6 and 7 may be formed with incomplete threads as at 40 for engaging a correspondingly threaded portion 41 at the outlet of the member 27'. With this construction upon insertion of the torch it may be given a half turn for bringing the tapered por-

tions 25', 26' into very firm sealing relationship. Then when the torch is to be removed for use, it may first be simply given a half turn in the opposite direction and then taken out and used as explained above in connection with Figs. 1 and 2.

In order to prevent any possible slight evaporation of fuel around the neck of the fuel can while in the lighter, the neck portion 16' as shown in Fig. 6 may be formed with a bayonet joint connection with the flange portion 15' and a sealing flange 42 may be mounted upon the upper surface of the wall 14' for engagement with a gasket 22' supplied on the fuel can as marketed. The bayonet joint connection may include protuberances as at 43 formed on the portion 16' for engaging thread-like indentations as at 44 on the flange portion 15'. With this construction, in order to permit the can upon insertion to be given a half turn for connecting the bayonet joint, the can and its housing may conveniently be made cylindrical as indicated in Fig. 5, whereas for forms such as shown in Figs. 1 and 2 the more conventional oval type of fuel can may be used, and with the housing of generally rectangular cross section for example. It will be understood that with the form of Fig. 6, upon inserting the can as shown and upon giving it a half turn to connect the bayonet joint, the flange 42 will be brought into firm sealing relationship with the gasket 22', thus preventing any evaporation or leakage of fuel into the space within the housing 10'.

If desired with forms of the invention such as shown in Figs. 1 and 2, means may be provided for insuring that the fuel can will always remain firmly seated with its wicking 17 in firm contact with the fuel absorbent in the compartment 11. For this purpose as shown in Fig. 8, the container cover 12' may have secured on its under side as by a rivet 45, a suitable leaf spring 46 for engaging the bottom of the can and thus normally urging the can downwardly when in its inverted position of use in the lighter.

While the invention has been described in detail with respect to particular preferred examples, it will be understood by those skilled in the art after understanding the invention, that various changes and further modifications may be made without departing from the spirit and 50

scope of the invention, and it is intended therefore in the appended claims to cover all such changes and modifications.

What is claimed as new and desired to be secured by Letters Patent is:

1. In combination, a lighter liquid fuel can adapted for retail sale and including a normally upstanding neck portion adapted to serve as a filling opening as well as an outlet, a body of 10 wick-like absorbent material secured within and filling said portion and protruding normally upwardly somewhat therefrom, said neck portion being constructed and arranged to receive a removable cap for covering said absorbent material and sealing the can during sale, a container and associated pyrophoric lighting means adapted to rest for use on a table or the like, a compartment forming the base portion of said container and substantially filled with fuel absorbent material, said compartment having an inlet 15 opening in its upper surface adapted to removably receive and embrace said neck portion with the can in inverted position, whereby the absorbent material in the neck portion of the can may 20 contact with that in said compartment, the upper portions of said container including a cavity for replaceably housing such cans, and having a quick-detachable cover.

2. A lighter construction comprising a container adapted to rest for use on a table or the like and having a base portion comprising a normally closed compartment substantially filled with fuel absorbent material, said compartment having an inlet in its top wall, a liquid fuel can adapted to rest in inverted position with its outlet in said fuel inlet and blocked by absorbent material, whereby the absorbent material in the compartment is kept substantially saturated with fuel but freely flowing fuel in the compartment 30 is substantially avoided, the upper portions of said container including a cavity for replaceably housing such cans, socket means extending from within said compartment at an angle upwardly and outwardly from the base of said cavity, a removable torch normally protruding through said socket means into absorbent material adjacent said inlet, and cooperating spark-striking means 40 associated with said torch and the container for lighting the torch.

ALEXANDER HARRIS.
